Ill., a corporation of Illinois

Application July 3, 1933, Serial No. 678,780

3 Claims. (Cl. 122—225)

This invention pertains in general to boilers and particularly to sectional boilers designed for the burning of oil or gas or other fuels requiring a large combustion space for efficient utilization 5 of available heating units.

One of the unfortunate phases of the adoption of oil or gas as a fuel for apartment and household boilers is found in the fact that, more frequently than not, coal burning grates have been 10 removed from boilers designed for the burning of coal, and oil or gas burning devices attached, without sufficiently altering the boilers to facilitate efficient burning of these fuels. The possibilities 15 of the fuel are thus largely neglected. This invention aims to provide a boiler especially designed for the burning of fuel oil or gas and will be found to possess many advantages residing in the construction thus afforded.

In general the object of the invention is to 20 provide improvements in boilers especially adapted for the burning of oil or gas. Particular objects of the invention will be alluded to as the features to which they pertain are hereinafter described.

25 In the drawings:

Fig. 1 shows a boiler comprising the invention partly in side elevation and partly in central vertical section;

Fig. 2 is an elevation looking from the back 30 of the front vertical boiler section, with the same removed from the boiler;

Fig. 3 is a sectional view taken on the line 3—3 of Fig. 2;

Fig. 4 is a section on the line 4—4 of Fig. 2;

Fig. 5 is an elevation looking from either side of any of the intermediate sections shown in Fig. 1;

Fig. 6 is a central vertical section through the 40 intermediate boiler section shown in Fig. 5;

Fig. 7 is an elevation looking toward the inside face of the rear boiler section;

Fig. 8 is a central vertical section on the line 8—8 of Fig. 7;

Fig. 9 is a vertical sectional view on the line 9—9 of Fig. 7;

Fig. 10 is a horizontal sectional view on the line 10—10 of Fig. 5;

Fig. 11 is a horizontal sectional view on the 50 line 11—11 of Fig. 5;

Fig. 12 is a perspective view of a closure member for a flue clean-out port;

Fig. 13 is a partial top plan view partially in section showing the manner of positioning and 55 locking the clean-out port covers; and

Fig. 14 is a vertical section on the line 14—14 of Fig. 13.

The boiler firebox or combustion chamber has the general shape indicated in Fig. 5, the combustion chamber 1 being rather pear shaped in cross-section, the fuel being blown in through the port 2 in the front boiler section burning within the combustion chamber, the flue gases passing upwardly over vertically extending bridges generally indicated as 3, in Figs. 5 and 10, and passing 10 downwardly through the vertical flues 4 on opposite sides of the boiler, thence into the horizontal bottom flues 5 which carry the flue gases rearwardly and bring them together at the flue passage 6 in the rear section, thence outwardly into 15 the smoke box 7 at the rear of the boiler from whence they pass off to a chimney.

The water is brought into the boiler at the bottom of the rear boiler section, as, for example, into the ports 8 and 9 shown in Fig. 7. 20 It can then pass from section to section through ports 11 provided in the bottoms of the intermediate sections and into the front section through ports 12. The water, upon being heated, rises through the water legs on opposite sides of 25 the combustion space, such as the water legs 13 in the intermediate sections, the water legs 14 in the rear section, and the water legs 15 in the front boiler section. Water chambers of the boiler sections are connected together by the 30 usual push nipples through an aligned passage 16 which extends through all of the boiler sections.

The boiler will be used in connection with hot water or steam systems, the various pipes such as 17 serving to carry the hot water or steam into 35 the heating system. The number of risers employed in any installation is, of course, a matter of choice.

The tie rods for connecting together the bottoms of the boiler sections do not form a part of 40 the invention but are indicated as 18 in Fig. 1, while the tie rods for holding together the tops of the boiler sections are indicated as 19 in Fig. 1.

At the front end of the combustion chamber there is provided a port 21 provided with a door 22 45 in which are mounted several plates of glass 23 providing an opening so that the condition of the flame may be observed.

At the rear of the combustion chamber there is provided another port 24 equipped with a 50 hinged relief door 25 to relieve suddenly accumulating pressures.

It will be observed that the flues leading from the combustion chamber are vertical flues carrying the flue gases downwardly until they are 55

delivered into the horizontal bottom flues 5. In order to facilitate the cleaning of these vertical flues, openings such as 26 are provided in the intermediate sections just above each vertical flue 4, these openings, however, being down some distance from the top surface of the boiler. It is necessary to keep these openings normally closed, and it is also advisable to finish off the top surface of the boiler to present a neat and uniform appearance. Accordingly, the closure members 10 are covers for the clean-out ports and are of an unusual shape, consisting of a curved outside plate 27 which conforms to the side walls of the boiler and also covers the top of the aperture 15 between adjoining boiler sections. A lower horizontal plate 28 in each of these closure members itself performs the actual function of closing off the port 26. Above this plate there is provided a second horizontal plate 29. The threaded bolt 31 20 passes through a locking plate 32, this plate being intended to be rotated by the turning of the bolt until its ends rotate into passage recesses 33 and 34 in the wall 35 which exists between each two boiler sections. Figs. 13 and 14 show this construction best and also show that the recesses 33 25 and 34 have top shoulders 36 and 37 against which the locking plate 32 will be raised upwardly by the bolt 31, thus forcing the flue port closure members tightly down into the wall 35.

30 It will be noted that the entire combustion chamber is surrounded on all of its side, top and bottom walls by water, permitting thereby a ready transference of the heat units from the burning gases to the water. The water legs 13 (see Figs. 35 5 and 10) also are amply subjected to the heat of the flue gases as the latter travel downwardly to the horizontal flues 5.

Reference to Fig. 10 of the drawings will disclose that a large amount of heat transfer area is obtained in the combustion chamber itself by making the walls thereof in a corrugated pattern without, however, interfering with the draft of the boiler, and obtaining a considerable increase in efficiency by having the walls jut out into the 40 combustion chamber where the swirling gases may impinge against them. It will be noted that this impinging action will not be casual but is made positive by the fact that the burning gases 45 must swirl around the protruding walls of the water chambers in order to find their way into the vertical gas flues 4 before they commence their downward travel. In fact the entrance to the top of each gas flue is found in a recess between the crests of the corrugations.

50 At the bottom of the combustion chamber we provide especially designed refractories 20 having slots 23 through which air may pass upwardly as it is admitted from the draft regulator 30. Of course, if the fuel burner actually employed 55 does not need secondary air supplied through the regulator 30 the latter may be closed. These refractories will radiate heat downwardly into the air spaces below them and thus serve to transfer heat to the water chambers below and by radiating 60 heat upwardly they contribute materially to promoting high combustion chamber temperatures in aid of complete burning of the fuel. The refractory 20 having only slight contact with the water-cooled surfaces of the firebox can attain 65 incandescence readily and quickly.

Along the rear wall at the end of the combustion chamber we provide a refractory wall 38 which will absorb heat from the burning gases and reflect and radiate heat back into them to thus 70 increase their temperature. A forwardly pro-

jecting ledge 39 will serve to divert downwardly and forwardly some of the gases that impinge against the refractory surface 38.

By making the firebox of the shape shown in the drawings, with its height about twice its width, and obtaining increased capacity merely by adding more intermediate sections in accordance with the size of the heating plant, we find that the burning of the fuel is accomplished with a high degree of efficiency. Ample space is thus 10 provided for the volatile gases to complete their combustion and this combustion can be completed within the firebox itself where all of the burning gas that is present obtains the benefit of the large mass action which is taking place. 15

The walls of the flues not only may be readily reached for cleaning through the ports 26, but also it is convenient to reach the side walls of the combustion chamber through these same clean-out ports 26, the tool being inserted over the top 20 of the vertical bridge walls 3. Thus the boiler may readily be kept in prime operating condition.

With the aid of the refractories, as shown, the combustion temperatures may be raised to increase 25 thoroughness of the burning of the fuel and to attain many ensuing advantages therefrom.

The present illustration indicates one embodiment of the invention in its present preferred 30 form. It should, however, be understood that various novel features of the invention may be incorporated in boilers differing somewhat from the illustrated construction, yet remaining within the spirit and scope of the appended claims. 35

We claim:

1. In an oil burning boiler having a combustion chamber defined by water back walls, refractory members for lining the bottom of said chamber having bosses for supporting them on the bottom 40 and side walls of said chamber whereby the major portions of the refractory members are out of contact with the water cooled walls, the front wall of the combustion chamber having an aperture through which fluid fuel may be projected against said refractory rear wall, and a refractory wall positioned against the rear wall of the combustion chamber having on its vertical front surface a forwardly extending central portion entirely surrounded by concave surfaces for 45 deflecting the combustion gases downwardly, laterally and upwardly from said portion.

2. In an oil burning boiler having a combustion chamber with an inlet at the front end thereof for an oil burner, said chamber having 55 water backed walls at its sides and bottom, refractory members lining the bottom of said chamber and a refractory wall at the rear end thereof extending upwardly a substantial distance provided with a central forwardly projecting portion 60 entirely surrounded by concave surfaces shaped for deflecting combustion gases impinging thereagainst downwardly, laterally and upwardly in a uniform manner.

3. A sectional boiler comprising a plurality of 65 sections when assembled providing water containing spaces defining the top, the bottom and in part the side walls of the combustion chamber of the boiler, said sections also providing a plurality of flues communicating with the upper 70 portion of the combustion chamber and leading laterally outwardly thence downwardly between the water containing spaces at the sides of said chamber, said sections also providing a pair of spaced apart horizontal flue passages extending 75

beneath the bottom of said chamber and each entirely surrounded by water containing spaces, said downward flues being connected to said horizontal flues, a smoke outlet connected with the horizontal flues, and return water inlets located in each section laterally of and below said horizontal flues, the walls of the horizontal flues and the water containing spaces surrounding them

being shaped to induce the returned water while being heated to flow centrally inwardly thence upwardly between said horizontal flues against the bottom of said chamber thence laterally outwardly and upwardly past the sides of the 5 chamber.

CHARLES A. OLSON.
JOHN P. MAGOS.
